UNITED STATES PATENT OFFICE.

ALFRED VICTOR DES MOINEAUX, OF DENVER, COLORADO.

DETACHABLE HEEL.

Application filed June 30, 1923. Serial No. 648,770.

To all whom it may concern:

Be it known that I, ALFRED VICTOR DES MOINEAUX, a citizen of the United States, residing at Denver, in the county of Denver and State of Colorado, having invented certain new and useful Improvements in Detachable Heels, of which the following is a specification.

This invention relates to means whereby 10 the wearing portion of a shoe heel can be quickly and easily detached and replaced by another portion without it being necessary to damage the permanent portion of the heel and without the use of nails, pegs or other 15 devices.

Another object of the invention is to provide a simple and novel means for locking the detachable portion to the permanent portion of the heel.

20 Still another object is to so construct the attaching means that there will be no vibration or movement between the fixed and detachable portions of the heel.

25 A further object of the invention is to provide means whereby a leather heel may when desired be replaced by a rubber heel and whereby a hob nailed heel may be placed upon the shoe when desired.

30 Other objects and advantages reside in the detail construction of the invention, which result in simplicity, economy, and efficiency, and which will become more apparent from the following description.

35 In the following detailed description of the invention reference is had to the accompanying drawing which forms a part hereof. Like numerals refer to like parts in all views of the drawing and throughout the description.

40 In the drawing:

Fig. 1 is a perspective view of a shoe showing the invention in place.

45 Fig. 2 is a perspective view of the stationary metal holder which may be attached either to the permanent portion of the heel or to the sole of the shoe.

Fig. 3 is a similar view of a detachable rubber heel.

50 Fig. 4 is a top plan view of the stationary metal holder.

Figs. 5 and 6 are end and side elevations, respectively, of the same.

Fig. 7 is a detail view of the locking lever.

55 Fig. 8 is a top plan view of the upper plate as used on rubber heels.

Figs. 9, 10 and 11, are side end and bot-

tom views respectively, of the upper and lower plates combined, as used on the rubber heels.

Fig. 12 is a plan view of a detachable 60 leather heel.

Figs. 13, 14, and 15 are end, side and bottom views respectively of a detachable leather heel carrying hob nails.

Figs. 16 and 17 are a detail end and bottom views respectively of the two plates employed on leather heels.

Throughout the description the upper part of the heel, shown at 22, will be referred to as the permanent heel and the lower or detachable part, shown at 18, will be designated simply the heel.

The invention comprises a plate 24, which has the contour of a heel and which is provided with countersunk openings 23 through which it is tacked or screwed to the permanent heel 22. The curved edge of the plate 24 is turned inward, as shown at 20, forming a marginal groove 21, the breast of the plate is left open, as shown at 25.

At the mid-point of the breast 25 the plate 24 is turned upward and formed in a loop 26. A locking lever 29 is secured on a pivot pin 30 in the loop 26, the lower extremity thereof projecting below the lower surface of the plate 24. Indentations 32 are formed in the face of the loop 26 to each side of the pivot pin 30 to maintain the locking lever 29 in the vertical position. The loop is of resilient material so that it will spread and allow the lever 29 to be forced under the indentations 32 which will hold the lever in any desired position. When in place the loop 26 extends upward on the breast of the permanent heel 22, as shown in Fig. 1.

On leather heels, as shown in Figs. 12 to 17 inclusive, two plates 44 and 45 are secured. The plate 44 has a contour and size corresponding to the outline of the inward turned edge 20 of the plate 24, and the plate 45 has a contour and size corresponding to the channel 21 of the plate 44, so that the two plates, 44 and 45, will set snugly into the plate 24. Plates 44 and 45 are provided with holes 42 by means of which the plates are secured to the heel with nails or screws. When in place on a shoe heel the plate 44 is placed against the heel and, since the plate 45 is the largest, a channel 46 will be formed between the plate 45 and the heel.

To place the heel on the permanent heel 22, the locking lever 29 is forced to one side

under one of the indentations 32. The plate 45 is now slid into the channel 21 until firmly in place. The locking lever 29 is forced to the vertical position in which it will be held by the indentations 32. The heel is now securely locked in place. The removal of the heel is, of course, the reverse of this process.

When the heels are of rubber, two plates 10 37 and 34, similar in size and contour to the plates 44 and 45 respectively, are employed. The plate 34 is provided with tongues 35 which engage in openings 39 in the plate 37 and are bent over, as shown 15 in Fig. 11, to secure the two plates together. The plate 37 is provided with hook shaped projections 38 which are moulded into the rubber heel, and serve to hold the plates in place. The operation and use of the rubber 20 heel is similar to the leather heel previously described.

In Figs. 13, 14 and 15, an alternate form of a leather heel is shown, which is provided with hob nails 43. This heel is also provided with attachment plates 44 and 45 and is interchangeable with the other heels.

While a specific form of the improvement has been described and illustrated herein, it is desired and understood that the same 30 may be varied, within the scope of the appended claims, without departing from the spirit of the invention.

Having thus described the invention what I claim and desire secured by Letters Patent is:

1. In a detachable heel a holder, having a marginal channel, adapted to be permanently secured to a shoe; a plate, having a marginal flange, adapted to be permanently 40 secured to said heel, said flange being arranged to engage in said channel and means for holding said flange in engagement with

said channel, said means comprising a lever pivoted on said holder and engaging the breast of said heel, and resilient projections 45 on said holder for maintaining said lever in any desired position.

2. In a detachable heel comprising a stationary part and a detachable part, means for locking said detachable part in place 50 comprising a lever pivoted to and arranged to extend below the stationary part of the heel and resiliently mounted obstructions arranged to engage and hold said lever in any desired position.

3. In a detachable shoe heel having a holder secured to the face of the permanent portion of said heel, a loop shaped clamp formed on said holder, and extending upward at the breast of said heel and a lever 60 pivoted in said clamp and arranged to extend below said holder.

4. In a detachable shoe heel having a holder secured to the face of the permanent portion of said heel, a resilient loop shaped 65 clamp formed on said holder at the breast of said heel; a lever pivoted in said clamp and arranged to swing below said holder and projections in said clamp for engaging and holding said lever in position.

5. A lock for two part detachable shoe heels comprising a resilient U-shaped clamp arranged to be secured to one part of said heel; a tongue pivoted between the two sides of said clamp at its one extremity and arranged to engage the other part of said heel at its other extremity and projections in said clamp arranged to be engaged by said tongue to flex said clamp and hold said tongue in any desired position.

In testimony whereof I have signed my name to this specification.

ALFRED VICTOR DES MOINEAUX.
